FOUNTAIN CABINET UNIT

David C. Smith and Werner Livingston,
Denver, Colo.

Application August 28, 1950, Serial No. 11,964

Term of patent 14 years

(Cl. D2—3)

To all whom it may concern:

Be it known that we, David C. Smith and Werner Livingston, citizens of the United States, residing at Denver, State of Colorado, have invented a new, original, and ornamental Design for a Fountain Cabinet Unit, of which the following is a specification, reference being had to the accompanying drawing forming a part hereof.

Fig. 1 is a front perspective view, taken from a position at one side, of a fountain cabinet unit embodying our new design; and

Fig. 2 is a perspective view, taken from the opposite side, of the fountain cabinet unit of Fig. 1, with the bottom portion broken away for convenience of illustration.

The dominant features of our design reside in the portions shown in full lines.

We claim:

The ornamental design for a fountain cabinet unit, as shown and described.

DAVID C. SMITH.
WERNER LIVINGSTON.
